UNITED STATES PATENT OFFICE

2,386,069

CAN DOUBLE SEAMING MACHINE

Jacob H. Schurch, Los Angeles, Calif., assignor
to Angelus Sanitary Can Machinery Co., Los
Angeles, Calif., a corporation of California

Application December 18, 1942, Serial No. 469,736

1 Claim. (Cl. 113—24)

This invention relates to can making machinery and particularly pertains to a can double seaming machine.

In the construction of can double seaming machines of the general type disclosed in U. S. Letters Patent No. 2,052,620 issued to Henry L. Guenther September 1, 1936, a double seaming machine was disclosed which included a turret rotating upon a vertical axis and carrying a plurality of seaming heads and sets of chucks. In that type of machine cans were fed to a position between sets of chucks and thus held while the turret rotated upon its vertical axis and while the double seaming rollers of the seaming heads on the machine individually rotated around the lip of the can and an associated cap and formed a double seam. In view of the fact that these machines are used in placing caps on filled cans it is obvious that any violent disturbance of the cans would cause material to spill, and this material might be thrown outwardly due to the centrifugal motion imparted by the rotating turret. Since the machine is operating at a relatively high speed of approximately 200 cans per minute, it is necessary to insure that all the parts are thoroughly lubricated. Lubricating oil thus has a tendency to be thrown from the machine. Furthermore, the moving parts of the machine provide a hazard to the workmen, and it is desirable to enclose the machine to obviate the aforementioned objections and dangers. Such a machine requires a rigid superstructure to afford support for the bearings of the rotating parts, and also requires means whereby an adequate reservoir of lubricating oil may be maintained in the base structure of the machine while being completely separate from the material which may spill from the cans and such steam and wash-water as may be required to wash and clean the seaming heads and the can turrets from time to time.

The present invention contemplates the provision of a can double seaming machine including turrets and seaming heads, an overhead driving structure, and a timing structure in the base of the machine, the entire machine being enclosed, and an oil reservoir disposed in the base structure and separate from the compartment enclosing the turret mechanism.

The invention is illustrated by way of example in the accompanying drawing in which:

Figure 1 is a view in side elevation showing the machine with parts broken away and indicating the details of the present invention.

Fig. 2 is an enlarged fragmentary view in ele-

vation showing the construction of the guard ring.

Referring more particularly to the drawing, 10 indicates a base casting upon which is mounted a substantially cylindrical unitary housing 11. The housing is directly supported upon a guard ring 12 which is bolted to the base by cap screws 13 and to which the housing 11 is secured by cap screws 14. The details of the ring will be hereinafter described. Secured upon the upper end of the housing 11 by cap screws 15 is a jack shaft housing 16. Mounted in suitable bearings within this housing and disposed transversely thereof is a jack shaft 17 which carries a driving pulley 18 at one end and associated with which is a driving clutch 19. The jack shaft 17 carries a driving pinion 20 in mesh with a gear 21. The pinion 20 and the gear 21 are bevelled gears. The gear 21 is carried upon the upper end of a center shaft 22. The jack shaft housing 16 is formed with a reservoir 23 within which lubricating oil is contained for the gears and also for the upper elements of the turret. The details of construction of the turret may vary but are indicated in U. S. Letters Patent No. 2,052,620 issued to Henry L. Guenther on September 1, 1936.

The lower end of the turret shaft 22 extends downwardly through a bearing plate 24 which extends horizontally and is cast integral with the top of the base 10. Mounted upon the shaft 22 is a drive sleeve 25 for the turrets of the machine. This sleeve also extends downwardly through a bearing 24'. Suitable pressure grease members are provided to lubricate the shaft 22, the sleeve 25, and their bearings. The lower turret 27 of the machine carries an annular ring 28 which circumscribes its periphery and is formed with an apron 29 which extends outwardly and downwardly to provide a vertical lip 30. This lip fits over a vertical lip 31 formed as a part of the guard ring 12. Extending downwardly and outwardly from the guard ring 12 is an inclined wall 32 which terminates adjacent the circumference of the upper end of the base plate 24 and is sealed with relation thereto to provide an oil reservoir 33. The oil reservoir 33 circumscribes the bearing 24' and retains a quantity of oil within the reservoir 33. In order to equalize the air pressure within the reservoir 33 and within the base 10, it is desirable to provide an air vent leading outside of the reservoir and to atmosphere. This air vent includes a duct 34 extending horizontally within the base plate 24 and communicating with the reservoir at its

inner end. The outer end of the duct 34 is provided with a vent casting 35. This casting is formed with an inverted U-shaped duct 36, the inner end of which communicates with the duct 34 and the outer end of which extends vertically and downwardly so that extraneous material is not liable to clog it. The bend in the duct 36 occurs at a level above the normal level of lubricating oil within the reservoir 33. Thus, the member 35 prevents drainage of oil from the reservoir 33 and at the same time allows air to enter the reservoir to prevent an air lock. The member 35 is secured in place on the side of the base 10 by cap screws 37 and when this member is removed the oil is drained from the reservoir 33.

As previously stated, it is necessary to wash the seaming mechanism, and this is done by the use of hot water or steam. It is desirable to prevent this material from contaminating the oil in the reservoir 33. Thus, the diameter of the housing 11 is materially greater than the diameter of the lip 30 on the turret ring 28. This provides an annular opening 38 extending entirely around the housing and through which water, steam, and waste material may flow onto the inclined floor 32 of the guard ring 12 and pass outwardly through the spaces 38 between the reinforcing columns 39 which are arranged at spaced intervals around the ring between a lower bolting flange 40 and an upper bolting flange 41.

By arranging the base 10 with a complete cylindrical housing structure 11 secured thereupon and the jack shaft housing 16 rigidly secured on the top of the main housing 11, the entire structure will be held together firmly so that all the bearings will be maintained in alignment and there will not be any objectionable vibration of the parts of the machine as it operates at high speed. It is possible also to secure the star wheels and transfer discs in position upon the housing 11 and to thus support them rigidly.

In operation of the present invention the double seaming machine is assembled as shown in the drawing with the apron 29 of the turret ring 28 overhanging the lip 31 of the drain floor 32. Thus, the oil reservoir 33 will be sealed above the base plate 24 so that the lubricating oil may accumulate within the reservoir 33 to the overflow level indicated by a dotted line in Fig. 1. When the level of oil rises above the turn 36 in the overflow the excess liquid will drain off. It will also be understood that in the event that heavier liquids, such as water, should accumulate within the reservoir 33 with the oil they would arrange themselves at the bottom of the reservoir and would drain out in advance of the draining of the oil. In the event it is desired to clean the interior of the housing 11 and the double seaming mechanism, one of the housing doors 42 may be removed so that a spray of water or steam may be projected into the housing. This liquid and the extraneous matter washed from

the machine parts will flow downwardly through the annular passageway 38 and along the inclined drain floor 32 to the exterior of the machine. In the event it is desired to drain the lubricating oil from the reservoir 33 the member 35 may be removed to allow the liquid to flow through the duct 34. As previously explained, the possibility of an air lock within the reservoir 33 is prevented by the connection of the U-shaped duct 36 with the duct 34.

It will thus be seen that the structure here disclosed provides a can double seaming machine within which oil reservoirs for moving parts are maintained with the oil uncontaminated and in which the moving double seaming mechanism is housed to protect the workmen from it, and at the same time to provide facilities whereby the interior of the structure may be washed and the waste water drained away without contaminating the lubricating oil. It will further be evident that the base and housing structures insure that a double seaming machine will be provided which is compact in design, rigid in construction, and will hold the moving parts without possibility of objectionable vibration.

While I have shown the preferred form of my invention as now known to me, it will be understood that various changes may be made in combination, construction and arrangement of parts by those skilled in the art, without departing from the spirit of my invention as claimed.

Having thus described my invention, what I claim and desire to secure by Letters Patent is:

In a can double seaming machine, a base structure having an upper relatively flat face, a guard ring secured upon said face, said ring being formed with an annular inwardly and upwardly extending drain wall defining a liquid reservoir, a cylindrical sealing lip along the inner upper edge of said wall, a housing agreeing in configuration with the guard ring resting upon and secured to said guard ring adjacent the upper outer edge thereof, said guard ring providing openings from the housing to the atmosphere above the drain wall, a rotary turret mounted within the area circumscribed by the guard ring and including a cylindrical apron extending downwardly and around the lip of the annular drain wall to form a liquid seal therewith, whereby liquid from around the turret and within the housing may drain outwardly through the openings in the guard ring, and a fluid trap comprising a duct extending outwardly from the bottom of the liquid reservoir to a point beyond the guard ring and there terminating in a U-shaped duct extending vertically, the bend in the duct occurring in a horizontal plane a predetermined distance above the bottom of the reservoir, and the discharge end of the duct communicating with the atmosphere at a point below the level of the outwardly extending portion of the duct.

JACOB H. SCHURCH.
